UNITED STATES PATENT OFFICE

HENRY L. KISER, OF ADRIAN, MICHIGAN

COIN-ACTUATED MECHANISM

Application filed May 9, 1929. Serial No. 361,733.

This invention relates to coin controlled mechanisms and particularly to a coin controlled mechanism for operating a machine for vending ice as disclosed in my pending 5 application for patent filed of even date herewith.

The general object of the present invention is to provide a very simple and compact means whereby a rotatable member may be 10 actuated by a second rotatable member, the last named rotatable member being adapted to receive a coin, and the coin acting to mesh with the second named rotatable member to thereby cause the actuation of the device.

15 A further object is to provide a device of this character which is very simple and smooth in its operation, which is not dependent upon complicated combination of springs and slides and in which the coin is readily released 20 after it has done its work.

Another object is to provide a mechanism of this character in which two coins must be deposited before the vending machine or other mechanism may be actuated.

25 Other objects will appear in the course of the following description.

My invention is illustrated in the accompanying drawings, wherein:—

Figure 1 is a rear face view of a coin mechanism constructed in accordance with my invention;

Figure 2 is a section on the line 2—2 of Figure 1;

Figure 3 is a top plan view of the construction shown in Figures 1 and 2;

Figure 4 is an inside face view of the coin disk 11;

Figure 5 is an inside face view of the coin disk 12.

Referring to these drawings, 10 designates a casing disposed within which are the disks 11 and 12. The plate 13 is disposed at the top of the casing and extends over a recess 10^a in the casing equal to the thickness

15 of the disks 11 and 12, this recess being formed to provide the two coin slots 14 and 15, the slot 14 being assumed for the reception of a dime, the slot 15 being also assumed for the reception of a nickel, the slots being of different thickness and different widths so as to

correspond to these coins. Of course, it will be understood that the slots may be of different cross sectional areas for coins of different dimensions.

The plate 13 is cut away at its lower edge 55 so as to fit partially around the disks 11 and 12, these disks being set side by side and in alinement with each other and with their peripheries nearly touching. The disk 11 has two recesses in its peripheral face, one 16, 60 having the diameter of half the diameter of a dime, while the recess 17 has a diameter of half the diameter of a nickel. Extending to that margin of the plate 13 which fits along the periphery of the disk 12 is a coin passage-way 18. The disk 12 is provided with two semi-circular recesses 19 and 20, the first recess being adapted to receive the nickel and the second recess being adapted to receive the dime. The disk 11 is cut away upon its periphery so as to provide two shoulders 21 and 22 and mounted upon the casing and associated with the cut-away portion of the disk is the stop pin 23. The disk 12 is likewise cut away upon its periphery so as to 70 provide two shoulders 24 and 25 and associated with this cut-away portion is the stop pin 26 extending from one wall of the casing. These stop pins 23 and 26 limit the rotation of the disks 11 and 12. 75

80 The disk 11 has to have a greater throw than the disk 12 and, therefore, the cut-away portion bounded by the shoulders 21 and 22 is longer than the cut-away portion of the disk 12 bounded by the shoulders 24 and 25. 85 The disks 11 and 12 are disposed within the casing and specifically mounted upon the front wall thereof by means of the shafts 27 and 28 which at their rear ends are mounted in the transversely extending strap 29. 90 Mounted upon the shaft 27 on the outside face thereof is a crank handle 30 whereby the shaft of the disk 11 may be rotated.

95 Mounted upon the shaft 28 on the inside of the casing is an arm 31, the extremity of which is provided with a pin 32 engaging a slot 33 in a link 34. This link 34 is pivotally engaged with a lever 35 which actuates the vending machine as clearly illustrated in my application for patent. When this link 34 is 100

pulled in the direction of the arrow in Figure 1, the trip of the vending machine will be operated and a block of ice will be discharged. Obviously this mechanism might be applied 5 to vending machines for other purposes without any departure from the spirit of my invention. A spring 36 acts to shift the arm 31 to the vertical position shown in Figure 1, the arm in this position being stopped from 10 further movement by the shoulder 24 bearing against the pin 26. The coin box 37 has an opening in its top which communicates with the passageway 38 defined by the two walls 39, this passageway being disposed immediately beneath the point of approximation of 15 the two disks 11 and 12. The coin box is, of course, provided with any suitable means whereby the coins may be removed therefrom.

The operation of this invention will be obvious from what has gone before. Upon the 20 dropping of a ten cent piece in the slot 14 and a five cent piece in the slot 15 and a rotation of the handle 30, the disk 11 will be rotated and will carry the nickel into engagement 25 with the recess 19 and disk 12. The nickel will act like a tooth in a gear wheel, causing an intermeshing engagement between the disks 11 and 12 which will rotate the disk 12 to a position where the pin 32 is at the end 30 of the slot 33. The ten cent piece then intermeshes causing a further rotation of disk 11 and the delivery of the merchandise. When the coin is discharged the spring 36 will bring 35 arm 31 back to initial position. No strain is placed on the coin at any time during operation.

If, however, a dime has also been inserted, the dime will continue the interlock between the disks 11 and 12 and a further rotation 40 will be given by the dime to the disk 12 causing a pull to be exerted upon the rod 34 or link which will actuate the trip of the ice delivering mechanism before the dime also escapes from between the two disks and drops 45 into the coin box. As soon as the dime has been dropped, the spring 36 will retract the arm 31. This will in no way affect the disk 11 and, therefore, there will be no kick back to the crank arm 30 as would be the case were 50 the two disks constantly intermeshing with each other.

It will be seen that the coin mechanism which I have described is very simple, that it is very compact and particularly that it 55 occupies only a very shallow space or casing. This mechanism provides for the use of two coins of different denomination (or two coins of the same denomination as far as that goes) and I find by the use of two coins, 60 that I secure a smoother and more positive operation than is secured when only one coin is used as a means for interlocking the two disks together for common rotation. I do not, however, wish to be limited to the use of 65 a driving disk 11 with two coin recesses and

a driven disk with two recesses. Neither do I wish to be limited to the exact construction shown, as obviously many minor changes might be made without departing from the spirit of the invention as defined in the appended claims. 70

I claim:—

1. A coin actuated mechanism including two disks, one of which is mounted upon a driving shaft and the other upon a driven shaft, the driven disk having in its periphery a coin recess, the driving disk having in its periphery a coin recess, means for guiding the coin into the recess of the driving disk, said coin when the driving disk is rotated, engaging in the recess of the driven disk and causing the common motion of the two disks, and means for limiting the rotations of the two disks, and means acting to urge the driven disk to its initial position. 80

2. A coin actuated mechanism of the character described including a driving and a driven disk disposed in the same plane and with their peripheries closely approximating, each of said disks having in its periphery a coin recess, stops limiting the rotation of the disks, means for positively rotating the driving disk, means for guiding a coin into the recess of the driving disk, the coin acting to cause the last named disk to rotate the driven disk and being discharged from between said disks when the disks have made a predetermined rotation, and means returning the driven disk to an initial position. 90

3. A coin actuated mechanism of the character described, including a casing, two disks mounted therein in the same plane and having their peripheries approximating each other at one point, means for positively rotating the driving disk, a member rotated by the driven disk, stops limiting the rotation of the two disks, each of said disks having in its periphery, a coin recess, means for guiding a coin into the recess of the driving disk, a rotation of the driving disk carrying said coin into the recess of said driven disk and then causing a common rotation of the two disks until the coin is discharged, and means urging the driven disk to an initial position. 100

4. A coin actuated mechanism of the character described, including a casing, two disks disposed in the same plane and having their peripheries approximating, one of said disks being a driving disk and the other a driven disk, each of said disks having a plurality of coin recesses in its periphery, a plurality of coin guides discharging into said recesses of the driving disk when the driving disk is in initial positon, means for rotatng said driving disk whereby the driving disk may be rotated to carry the coins into the recesses of the driven disk and cause the rotation of the driven disk until the coins drop out, and means yieldingly resisting the movement of 110

the driven disk under the action of the driving disk from its predetermined coin receiving position.

5. A coin actuated mechanism of the character described, including a casing, two disks disposed in the same plane and having their peripheries approximating, one of said disks being a driving disk and the other a driven disk, each of said disks having a plurality of 10 coin recesses in its periphery, means for guiding a plurality of coins to the coin recesses of the driving disk, means for rotating said driving disk whereby the driving disk may be rotated to carry the coins into the recesses 15 of the driven disk and cause the rotation of the driven disk until the coins drop out, means urging the driven disk to a predetermined coin receiving position, a shaft upon which the driven disk is mounted having an 20 arm and a link having a slot, the arm having a pin engaging said slot, the slot having a length sufficient to permit a free limited movement of the arm and driven disk under the action of one coin, the arm then acting under a continued rotation of the driven disk to 25 exert a pull upon said link.

6. A coin controlled mechanism of the character described, including a casing, a driving and driven disk mounted thereon in 30 the same plane and having their peripheries approximating, the driving disk having in its periphery two recesses disposed in conjunction successively, the casing having two coin guides directing coins into said recesses 35 when the driving disk is in predetermined position, stops limiting the rotative movement of the driving disk, the driven disk having two successive coin recesses in its periphery, stops limiting the rotation of said driven 40 disk, means urging the driven disk to a position with the advance coin recess disposed adjacent the point of approximation between the two disks, and a member actuated by the rotation of the driven disk.

45 7. A coin controlled mechanism of the character described, including a casing, a driving and driven disk mounted thereon in the same plane and having their peripheries approximating, the driving disk having in its 50 periphery two recesses disposed in conjunction successively, the casing having two coin guides directing coins into said recesses when the driving disk is in predetermined position, stops limiting the rotative movement of the 55 driving disk, the driven disk having two successive coin recesses in its periphery, stops limiting the rotation of said driven disk, means urging the driven disk to a position with the advance coin recess disposed adjacent 60 the point of approximation between the two disks, a member actuated by the rotation of the driven disk, a shaft upon which the driven disk is mounted and having an arm, and a link having limited sliding engagement 65 with the arm whereby a movement of

the arm under the actuation of the driving disk and the forwardmost coin will cause the arm to move without actuating the link and a further movement of the arm will cause the actuation of the link.

70 8. A coin actuated mechanism of the character described, including a shaft having an arm, a link, driving means for the shaft separated therefrom, means acting upon the deposit of one coin to cause the rotation of the shaft through a predetermined arc without affecting the link and whereby a further rotation of the shaft in the same direction consequent upon the deposit of the second coin will cause the movement of the link.

75 9. A coin actuated mechanism of the character described including a member to be actuated, an element for actuating said member and having limited movement with relation thereto, means for giving said element the aforesaid limited movement upon the deposit of one coin, and means acting upon the deposit of a second coin to permit the continued movement of the element to cause the movement of the actuated member.

80 In testimony whereof I hereunto affix my signature.
